PICTURE SLIDE HOLDER

William Bruce Pester, Ann Arbor, Mich., assignor to Sylvania Electric Products, Inc., New York, N. Y., a corporation of Massachusetts

Application January 23, 1957, Serial No. 44,565

Term of patent 14 years

(Cl. D61—1)

Fig. 2

Fig. 1

Fig. 1 is a side elevational view of a picture slide holder, showing my new design;

Fig. 2 is a top plan view;

Fig. 3 is an opposite side elevational view; and
Fig. 4 is an end elevational view thereof.

I claim:

The ornamental design for a picture slide holder, substantially as shown.
